US00D904173S

(12) **United States Design Patent** (10) **Patent No.:** **US D904,173 S**
Jin (45) **Date of Patent:** **** Dec. 8, 2020**

(54) **RACK**

(71) Applicant: **SHENZHEN YIYASU TECHNOLOGY CO., LTD**, Shenzhen (CN)

(72) Inventor: **Youquan Jin**, Shenzhen (CN)

(73) Assignee: **SHENZHEN YIYASU TECHNOLOGY CO., LTD.**, Shenzhen (CN)

(**) Term: **15 Years**

(21) Appl. No.: **29/747,478**

(22) Filed: **Aug. 24, 2020**

Related U.S. Application Data

(63) Continuation-in-part of application No. 29/728,626, filed on Mar. 19, 2020, now Pat. No. Des. 897,823.

Primary Examiner — Steven J Czyz

(57) **CLAIM**

The ornamental design for a rack, as shown and described.

DESCRIPTION

FIG. 1 is a perspective view of a rack showing my new design;

FIG. 2 is another perspective view of the rack shown in FIG. 1;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in the drawings depict portions of the rack that form no part of the claimed design.

1 Claim, 8 Drawing Sheets
